Inventor.

H. S. Seymour

Des. 1660

H. C. Seymour, of Troy, N. Y.
Bettors Patent No. 1660. Dated Sept. 23, 1862.

The schedule referred to in these Bettors Patent and making part of the same.

To all whom it may concern:

Be it known that I, H. C. Seymour, of Troy, in the County of Rensselaer, and State of New York, have invented or produced a new and original design for a Chair; and I do hereby declare that the following is a full, clear and exact description of the same, reference being had to the accompanying drawings, making a part of this specification, in which—

Figure 1. is a perspective view of my invention, constructed according to my design.

Figures 2. 3. 4. and 5. are sections of the same, taken respectively in the lines x. x, y. y, z. z, and z'. z'. Figure 1.

Similar letters of reference indicate corresponding parts in the several Figures.

This invention consists in having the rails or frame of the seat of the chair, as well as the front, legs and side and cross pieces of the back provided with a moulding, as hereinafter described.

A. represents the frame of the seat, B. of the chair, the external surface of which is provided with a moulding composed of an ovolo a, and cyma reversa b, divided by a fillet c, as shown in Figure 2. This moulding extends all around the seat frame A. with the exception of its back part.

The front surfaces of the front legs C. C, as well as the front surfaces of the side pieces D. D. of the back are provided with a moulding which is composed of a central projecting ovolo d, with a fillet e at each side, and a scotia f, as shown in Figure 4.

The upper back piece E. is provided with a moulding at its upper and lower edges composed of two ovolos g, g' as shown in Figure

Dec. 1660

3. The lower back piece F, is also provided with a similar moulding at its upper edge.

All the prominent parts thereof of the chair frame, that is to say, those parts which are foremost, or which the eye catches at a front view are provided with mouldings.

Having thus described my invention what I claim as new and desire to secure by Letters Patent, is -

The general configuration of the parts as herein shown and described, to form a new and original design for a chair.

Witnesses.
